UNITED STATES PATENT OFFICE.

JOHN K. VANDERBURGH, OF MARSHFIELD, OREGON.

SEPARATING THE SEDIMENTS, &c., FROM THE SACCHARINE JUICE OF SORGHUM.

SPECIFICATION forming part of Letters Patent No. 275,963, dated April 17, 1883.

Application filed January 17, 1883. (No model.)

To all whom it may concern:

Be it known that I, JOHN K. VANDERBURGH, of Marshfield, county of Coos, State of Oregon, have invented an Improvement in Separating 5 the Sediments and Suspended Impurities from the Saccharine Juice of Sorghum; and I hereby declare the following to be a full, clear, and exact description thereof.

My invention relates to a new and useful 10 process of and apparatus for separating the sediments, consisting of vegetable matter, insoluble earthy compounds, and othersuspended impurities, from the saccharine juice of sorghum, whereby the resultant juice will be 15 pure enough to readily granulate and form a large percentage of sugar.

My apparatus consists in an ordinary evaporator in which one or more compartments are formed at its head by transverse partitions or 20 diaphragms, the tops of which are below the level of the sides of the evaporator. In these compartments I may place removable perforated receiving-pans, as I shall hereinafter explain.

25 My process consists in admitting the pressed juice into the compartment, or, if there be more than one, into the first of the compartments at the head of the evaporator, heating it to the temperature of 210° Fahrenheit, (the 30 usual skimming process taking place meanwhile,) and allowing the top or pure juice to flow over the depressed top of the partition into the next compartment or into the main body of the evaporator, as the case may be. 35 During the heating process the heavy sediments of all descriptions sink and cannot flow over as suspensions into the next compartment, but must remain in the first compartment, from which they may readily be removed, the main 40 object being gained of removing the deposits from the juice at the beginning of the operation of making sirup or sugar. The presence of these suspended and deposited impurities and the difficulty of removing them has made 45 the manufacture of sugar from sorghum almost impracticable, and consequently little has been made from it but coarse sirups, which are used as such or sold to the refiners for purification. When these impurities are

present the sugar will not granulate. These 50 impurities must be wholly removed from the juice and at the first period of the operation.

Referring to the accompanying drawings, Figure 1 is a perspective view of my apparatus. Fig. 2 is a longitudinal vertical section.

Let A represent any form or kind of boiler or evaporator, which may be supposed to be in proper relation with a suitable furnace, (not here shown,) whereby the necessary heat may be supplied. In one end of the evaporator, which, 60 because of the liquid being supplied from that end, is called the "head," there are here shown two compartments, B B', formed by the partitions or diaphragms C C'. These partitions are not quite as high as the sides of the evaporator, as will be seen. I may have a single compartment or a number of them; but the whole of them should not occupy more than about a fourth of the length of the evaporator in order to provide sufficient space for the reception of the pure juice. In the compartments may be hung perforated pans D, which may be removed when necessary.

The juice, when pressed from the cane, is fed in the usual manner to the evaporator at 75 its head. It enters the first compartment, B, and is heated to a temperature of 210° Fahrenheit. Under this temperature the impurities, which are heavy, sink in the compartment and are caught in the pans. The light and pure 80 juice, rising to the top, will flow over the top of the partition C, the supply being kept up. In the compartment B' it undergoes the same operation, and flows over the partition C' into the main body of the evaporator as comparatively pure juice. The impurities which rise to the surface as scum must be removed during the process in the usual manner; but the heavy impurities of all kinds, under the influence 85 of the heat, are separated from the juice, and, 90 sinking, remain behind in the compartments, so that the juice in the foot of the evaporator is free of them and will granulate, as desired.

The pans D, when full of sediment, may be removed. These, being perforated, do not confine the juice, but simply catch the sediments and furnish an easy means for removing them.

A single compartment at the head of the

evaporator may be sufficient; but if not there can be as many as may be found necessary to perfect separation.

Having thus described my invention, what I claim as new, and desire to secure by Letters Patent, is—

An evaporator, A, having at its head one or several compartments, B B', formed by transverse partitions C C', the tops of which

are lower than the sides of the evaporator, in combination with removable perforated pan or pans D, hung in said compartments, substantially as and for the purpose herein described.

In witness whereof I hereunto set my hand.

JOHN K. VANDERBURGH.
